UNITED STATES PATENT OFFICE

AUGUST J. WIEGAND, OF CHICAGO, ILLINOIS, ASSIGNOR TO GRIGSBY-GRUNOW COMPANY, OF CHICAGO, ILLINOIS, A CORPORATION OF ILLINOIS

HORN FOR LOUD-SPEAKERS

Application filed August 1, 1925. Serial No. 47,446.

My invention relates to horns for loud speakers and has to do more particularly with horns of the above character adapted to be attached to a receiver or for a receiver attached to the horn for use as a radio loud speaking receiver, although my invention is not intended to be limited to devices of this particular character.

There are various features and advantages 10 in my improved horn, and these will be more particularly pointed out in the ensuing part of the specification and appended claims.

For a better understanding of my invention reference is to be had to the accompanying drawing, in which—

Fig. 1 is a side elevation of the preferred form of my invention mounted upon a base and standard for table use;

Fig. 2 is a vertical sectional view along the 20 line 2—2 of Fig. 1, looking in the direction of the arrows indicated thereon;

Fig. 3 is a bottom view of Fig. 1; and

Fig. 4 is a sectional view through the central webbed portion of the horn, showing it 25 mounted upon a block which may extend from the wall or base of a cabinet.

Referring now more in detail to my invention, I provide a horn consisting of a neck portion A continuing into a bell portion B 30 and shaped in the form of a goose-neck, U shape, or single reverse curve. The horn is preferably made up of a suitable moldable material and I preferably use a sheeting made up of a pyroxylin plastic compound such as 35 pyralin which may be molded into the desired shape.

The horn is preferably built up of two like but oppositely formed halves 5—6 molded into the goose-neck or reverse curve shape 40 and attached or fastened together at abutting faces along a median line throughout the horn. In the preferred form of my invention as shown herein these abutting faces are made up of radially extending flanges as 45 7—8, which are fastened together by a suitable cement. This flange construction is preferable where a thin sheet-like material of the above character is used, although when using other plastic compounds such as 50 fiber pulp, etc. the material may be heavy

enough so as to have the two contiguous edges of the halves cemented or secured together in some other suitable way.

Now as to the radial flanges for securing the two halves together, the outer flanges 55 7—8 are preferably formed outwardly or away from the center of the horn so as not to obstruct the inner passage.

In constructing the reverse curve or goose-neck type of horn as herein illustrated, I 60 preferably extend the inner abutting flanges so as to form a web made up of the two flanged portions 9—10. This webbed construction thus stiffens the horn and strengthens it and also minimizes the vibration of 65 the wall and thus reduces the harmful resonant effects. Also it provides a greater and more positive fastening surface. Furthermore, this webbed wall is arranged as a supporting element of the horn, that is the horn 70 is supported from this web either from a table standard as C shown in Figs. 1, 2 and 3, or it may be attached to a wall or base block E within a cabinet or otherwise as shown in Fig. 4. This takes the strain off 75 the tube.

In the base or table standard C I provide a suitable base member 11 for supporting the attaching or carrying arms, which as shown herein comprise two sheet-metal like halves 80 12—13 bowed out so as to clear the neck A of the horn and then come together at their upper ends to form a clamp in which the web of the horn is held. The lower ends of the members 12—13 extend down into the base 85 and then are clamped against a lug 14 by a clamping screw 15.

The members 12 and 13 are clamped to the webs 9 and 10 at the top thereof by nuts and bolt 15¹, a pivot thus being formed by means of which the horn is secured to the upright stud. Thus the horn may be readily adjusted to any angle, pointing it downwardly, horizontally or upwardly, which is often desirable.

In forming up a horn of the character shown herein I preferably take a sheet of pyralin of the proper development so as to be moldable into the desired shape, and heat it sufficiently so that it may be plastic enough 100

to be formed between pressure molding dies. In heating the pyralin I preferably dip it into water hot enough to soften the pyralin to a moldable state, but not hot enough to burn or damage the finish on the face of the sheet. 5 The sheet is then placed between the proper molds and pressed into shape, after which it is chilled so that it will retain its form. The two like but oppositely formed halves are 10 then suitably fastened together along the median line of the horn, preferably by a suitable cement.

I have shown a receiver or telephonic unit F attached to the neck of the horn, such unit 15 being of any desired and suitable type preferably attached to the neck.

What I claim as new and desire to secure by United States Letters Patent is—

1. A horn for loud speakers and the like 20 having a neck and continuing bell portion comprising two like but oppositely formed halves of suitable moldable plastic sheet material provided with abutting edges on the median plane for fastening the two halves 25 together to form a single unitary structure, the flanges between the neck and bell being extended to provide a web of double thickness.

2. A horn for loud speakers and the like 30 consisting of a tubular sound carrying member formed in a U shape, and a horn supporting web extending across between and connecting the legs of the tubular member as an integral portion thereof.

3. A horn for loud speakers and the like 35 consisting of a tubular member having a neck and continuing bell portion formed in a U shape, and a horn supporting web extending across between and connecting the neck 40 and bell portions.

4. A horn for loud speakers and the like 45 consisting of a tubular member having a neck and continuing bell portion formed in a U shape, and a horn supporting web extending across between and connecting the neck and bell portions, said tubular members including two complementary sections and the web being a continuation of such sections.

5. A horn for loud speakers and the like 50 consisting of a U tubular member having a neck and continuing bell portion comprising two symmetrical but oppositely formed halves of suitable sheet material provided with abutting flanges extending on the median plane for fastening the two halves together to form a single unitary structure, said flange extending across between and connecting the neck and bell portions as a web.

6. A horn for loud speakers and the like 60 consisting of a U tubular member having a neck and continuing bell portion comprising two symmetrical but oppositely formed halves of suitable sheet material provided with abutting flanges extending on the median plane for fastening the two halves to-

gether to form a single unitary structure, said flange extending across between and connecting the neck and bell portions as a web, and means for supporting the horn by said web.

In witness whereof, I hereunto subscribe my name this 13th day of February, 1925.

AUGUST J. WIEGAND.
